UNITED STATES PATENT OFFICE.

JOHN H. WEAVER, OF PHILADELPHIA, PENNSYLVANIA.

ASH DISPOSAL.

Application filed December 7, 1920. Serial No. 428,869.

To all whom it may concern:

Be it known that I, JOHN H. WEAVER, a citizen of the United States, residing at Philadelphia, in the county of Philadelphia, 5 State of Pennsylvania, have invented a new and useful Ash Disposal, of which the following is a specification.

The invention relates primarily to ash disposal in connection with means for controlling the dust arising therefrom.

The object is to provide, in connection with furnace draft controlling means, means whereby the ashes or other dust containing substance may be removed from the stove 15 or furnace and deposited into a suitable container, and the dust usually arising therefrom, controlled and conveyed away to the flue of the stove or furnace. In other words, the object is to provide a convenient place 20 of deposit for the ashes and, at the same time, utilizing by means of a special furnace draft control, the pneumatic pressure of the draft in the chimney flue for carrying away the volatile part of the ashes, or the 25 dust that arises as a result of the disturbance of the ashes.

The invention comprises convenient means whereby the draft may be utilized for the dust control, without impairing the draft of 30 the furnace or stove, except when the ashes are actually being shifted or disturbed.

The invention comprises means whereby the means controlling the pneumatic pressures in the dust area, also provide efficient 35 and convenient means for regulating the fire in the furnace or stove.

The invention comprises means for accurately indicating the condition of the draft with respect to the furnace or stove.

40 The invention comprises convenient means whereby the ashes may be sifted in a partly confined space and within the influence of the draft, or the below-atmospheric pressure caused thereby, so that the dust resulting from said sifting is carried away.

My invention also comprises improvements in the special construction and arrangement of the means for securing the above result.

50 Referring to the drawings which illustrate merely by way of example a suitable embodiment of my invention:—

Fig. 1 is a front elevation.

Fig. 2 is a side elevation.

55 Similar numerals refer to similar parts throughout the several views.

The casing or chamber forming body 5, comprises the slightly tapered approximately cylindrical part 6 and the top portion 7 having upwardly inclined walls and 60 provided at its top central portion with the flange 8 into which is fitted a collar or section of pipe 9 adapted to be connected by means of a suitable conductor, not shown, to the chimney flue of a stove or heater. 65 The cylindrical part 6 is provided in its lower half with the large opening 10, and the hinged closure or door 11. Above the opening and door 11, is a smaller opening 12, which is usually not provided with a 70 closure. This opening 12 is shown with an arched upper wall 13.

At the bottom of the collar or pipe section 9 is provided the damper member 14, secured to the lever 15, with a slight play, 75 by the loosely fitting screw 16. Lever 15 is secured, against rotation, to the shaft 17 by means of the set-screw 18. Shaft 17 is journaled in the block 19 and the bearing formed in the box 20, both journal bearings 80 secured to the top 7, of the casing 5. To one end of shaft 17 is secured the operating handle 21, locked in position of proper adjustment by the set-screw 22. This handle member 21 is preferably provided with a sector-shaped formation 23 having notches 24 and suitable indication marks to show the position of the damper 14. The notches 24 are adapted to cooperate with the spring member 25 secured to the top of the box 20, and 90 adapted to maintain the damper operating handle in any desired position of arbitrary adjustment.

In the body of the casing wall 6 are provided suitable recesses or ledge-forming elements, as at 26, for supporting one end each of a pair of horizontal supporting members 27. The other ends of these members 27 are adapted to rest on the upper edge of the door or closure 11, preferably in slight recesses 28, to prevent lateral displacement. 95

The members are also provided with suitable shoulders 29, or other suitable device for engaging the walls of the casing and thereby preventing longitudinal displacement of the said members.

The members 27 are provided to support the sieve member 30, which may consist of an open frame with a screen bottom, and suitable flanges 31 for maintaining the frame upon the members 27. The dimensions of the sieve member 30 are such as to 105 110

permit horizontal movement of same within the casing or chamber 5. And hence, the sieve is supported on the members 27 so that it may be reciprocated thereon. The handle 32 is connected with sieve 30 for the manual operation of the same.

In operation, the collar or pipe section 9 is connected either directly or indirectly to the flue; that is, it may have a pipe running 10 directly from the collar 9 to the flue in the chimney, or it may be connected to the smoke pipe leading from the heater or furnace to the flue.

The purpose of the opening 10 controlled 15 by door 11, is to admit into the chamber of the casing 5 a suitable box, tub or other container for the ashes. The door 11 is then closed. When it is desired to deposit 20 ashes into container, the damper 14 is opened establishing communication between the chimney flue and the chamber. The ashes or other dust laden material are introduced through the opening 12, into said container and the dust arising therefrom 25 is carried off through pipe 9 to the chimney flue.

In case it is desired to sift the ashes before depositing the same in the container, the sifter 30 is used, resting upon the slides 30 or members 27. It will be noted that the top of the sieve or sifter 30 extends only a slight distance above the bottom of opening 12 so that the ashes may readily be shoveled into the sieve or sifter through 35 said opening. The sifter is agitated or reciprocated by means of the handle 32 and the dust arising therefrom is carried off as above described. The sieve 30 is readily inserted into and withdrawn from the chamber through the opening 12.

The damper control is especially useful when the chambered body is connected with the flue or the smoke pipe of a stove or heater; in which case the damper 14 may 45 readily be set to check or increase the draft of the stove or heater as desired. The position of the damper is indicated at all times by the position of the end of spring 25, co-operating with the notches 24, with respect 50 to the indications or marks on the face of the sector-dial 23. The required position of the damper is only disturbed, if at all,

when sifting or depositing ashes or other material in the receptacle.

Immediately after the conclusion of such 55 operation, the damper 14 is again set in the position desired, with respect to the condition of the fire and the temperature required.

The advantage of making the cylindrical 60 chamber forming body slightly tapering is to permit the nesting of several such structures for purposes of transportation.

The device is extremely simple, compact, neat and efficient, and contributes greatly 65 to maintaining cleanliness in the house or apartment where it is used. It also provides convenient means for further control of the fire.

What I claim is:—

1. In an ash disposal device, the combination of a chamber forming structure, having an opening in its side wall extending from near the bottom to near the top of said structure, the upper part of said opening having a smaller horizontal dimension than the lower part of said opening, a movable closure for the lower larger opening, and regulatable means for connecting the interior of the structure with a flue. 70

2. In an ash disposal device, the combination of a chamber forming structure, having an opening in its side wall extending from near the bottom to near the top of said structure, the upper part of said opening having 75 a smaller horizontal dimension than the lower part of said opening, a movable sifting device having its upper margin near the bottom of the smaller opening, a movable closure for the lower larger opening, and 80 regulatable means for connecting the interior of the structure with a flue.

3. In an ash disposal device, the combination of a chamber forming structure, having an opening in its side wall extending 85 from near the bottom to near the top of said structure, the upper part of said opening having smaller horizontal and vertical dimensions than the lower part of said opening, a movable closure for the lower larger opening, and regulatable means for connecting the interior 90 of the structure with a flue.

JOHN H. WEAVER.
